(57) **CLAIM**

What is claimed is the ornamental design for a hanging plush toy, as shown and described.

DESCRIPTION

FIG. 1 is a top view showing the hanging plush toy of Applicant's invention.

FIG. 2 is a left side view of the hanging plush toy of Applicant's invention.

FIG. 3 is a frontal view of the hanging plush toy of Applicant's invention.

FIG. 4 is a right side view of the hanging plush toy of Applicant's invention; and,

FIG. 5 is an underside view of the hanging plush toy of Applicant's invention.

In the Figures, the dashed lines represent stitching. The broken dash-dot-dot lines showing environmental structure which define the bounds of the claimed design form no part thereof.
